MILL ROLL STAND

Karl Sieg, Philadelphia, Pa., assignor to Samuel M. Langston Co., Camden, N. J., a corporation of New Jersey

Application June 10, 1947, Serial No. 753,689

14 Claims. (Cl. 242—58)

1

This invention relates to mill roll stands for the same general purpose as that shown in the Behrens Patent 2,405,637, issued August 13, 1946, and in which a heavy roll of sheet material is supported at the ends of a pair of pivotally mounted arms which may be moved toward and from each other along a cross-shaft to engage rolls of different lengths, and may swing in vertical planes to raise and lower the roll. This roll is rotatably supported at the ends of the arms so that the sheet material may be unwound and delivered to a machine which may perform any of a variety of operations thereon.

In many machines of this general type the pair of arms are mounted on the rotatable cross-shaft, and the power for effecting the raising and lowering of the heavy roll is usually applied to the shaft through gearing. The movement of the arms toward and from each other to engage the roll, and the simultaneous movement of the arms in the same direction to shift the roll axially, is effected by sliding the arms along splines or keys on the shaft.

Where the roll is of very large diameter and great length, it is necessary to make the cross-shaft also of large diameter. As the keys and keyways are subjected to great pressure in resisting relative angular movement of the arms and shaft, it is difficult to slide the arms along the shaft in adjusting the roll endwise to the proper position after it has been lifted. Furthermore, if gears be employed for rotating the shaft to lift the roll, the gear teeth must be large and strong to resist the very great stress exerted both during the lifting operation and while holding the roll in raised position.

One of the main objects of the present invention is to provide an improved construction of roll lifting, supporting and adjusting means, whereby it is not necessary to use either keys or keyways on the shaft, or any gear on the shaft for effecting the raising movement.

As one important feature of my invention the pivoted roll supporting arms are mounted on carriages slidable along the main frame, and are raised and lowered by the action of jack screws also mounted on the carriages, rather than by the rotation of a shaft supporting the arms.

As a further important feature, threaded means are provided for simultaneously moving the carriages, together with the roll supporting arms and their lifting jacks, toward and from each other, to engage or disengage the ends of the roll. This means preferably includes a shaft having right and left hand threads.

2

As a further important feature, means are provided for simultaneously moving the carriages, together with their arms and lifting jacks, in the same direction, to properly line up the sheet with the machine to which it is to be delivered, and this means preferably acts to move endwise the aforementioned shaft.

As a further important feature the roll supporting, lifting and adjusting mechanisms are provided in duplicate on opposite sides of the main frame, so that one roll on one side of the frame may be lifted and held in proper sheet delivery position while a sheet is being unwound from a roll on the other side of the frame; or so that sheets of the same or different widths may be simultaneously unwound from two rolls and delivered in slightly overlapping relationship, to produce a product of greater width than that of the sheet of any roll which may be in stock at the time.

As a further important feature, means are provided whereby one arm may be raised or lowered in respect to the other to slightly tilt a roll in case it be wound more tightly at one end than at the other, and to prevent tearing of the sheet.

As a further feature, there are provided a plurality of electric motors mounted on the machine so that the various movements of the arms may be easily and quickly effected.

Various other important features as well as advantages will be pointed out hereinafter, or will be apparent from a consideration of the apparatus illustrated, and the following description.

In the accompanying drawing showing certain embodiments of a machine embodying my invention:

Fig. 1 is a perspective view of one side of the machine.

Fig. 2 is a sectional detail of a clutch used when raising or lowering one arm in respect to the other.

Fig. 3 is a plan view, partly in section, showing one arm.

Fig. 4 is a sectional detail at right angles to a part of Fig. 3.

Fig. 5 is a side view, partly in section, of the arm.

Fig. 6 is a side view, partly in section, of the outer end of an arm.

Fig. 7 is a vertical section through a part of the frame, and showing the carriage and roll lifting mechanism.

Fig. 8 is a perspective view, partly in section, of the arm lifting means.

Fig. 9 is a perspective view of the drive end of the machine, similar to the left hand end of Fig. 1, but showing all three adjusting motors at the same end.

Fig. 10 is a sectional detail of the clutch shown in Fig. 9.

Fig. 11 is a perspective view of a portion of the drive end showing the means for moving the arms simultaneously in the same direction.

Fig. 12 is a somewhat diagrammatic plan view showing arms positioned for supporting two rolls with the sheets in slightly overlapping relationship, and

Fig. 13 is a diagrammatic end view showing the simultaneous delivery of two sheets.

The main frame, as shown particularly in Figs. 1 and 7, includes a pair of end frame elements, preferably in the form of parallel vertical plates 23 and 23a, which may be secured in selected fixed positions by means of base flanges 21. Between these two end frames is a transversely extending frame element constituting a cross frame, and preferably in the form of a plate 22 disposed in a vertical plane and secured to and supported by the plates 23 and 23a. As shown particularly in Fig. 7, the plate 22 has top and bottom plates 23 and 24 disposed in horizontal planes. The roll supports are carried by these plates 23 and 24, and are adjustable along the length thereof and angularly in vertical planes at right angles to the plane of the vertical plate. The top and bottom plates 23 and 24 are each provided on their under and upper surfaces, respectively, with two pairs of rails 25, one pair being on each side of the vertical central plate 22. The plates 22, 23 and 24 in effect form an I beam.

The roll of sheet material is supported by a pair of arms 26 mounted on a sleeve 26a journaled in bearings 28 on a carriage movable along the rails of the main frame. Concentric with and inside of the sleeve is arranged a shaft 27, the ends of which are supported in the end frame plates 23 and 23a. Each carriage is preferably formed of a casting including a pair of side plates 29 which are connected by a back plate 30 and have at their outer edges the bearings 28 for the sleeve 26a. As shown in Fig. 7, the carriage at its upper end is provided with a roller 31 fitting between the two parallel depending rails 25 of the top plate 23 and a roller 32 for engaging the under surface of one of the rails. Likewise, at the lower end of the carriage there are similar rollers 31' and 32' engaging the rails 25 of the lower plate 24. Thus the carriages carrying the arms may move transversely of the frame, and are prevented from tilting.

For moving the arms toward and from each other to engage or release a roll of paper, the shaft 27 has one end portion provided with right hand screw threads and the other end portion provided with left hand threads which engage nuts 34, as shown in Figs. 3 and 4, and which are normally locked against rotation by a spring pressed pin 35 engaging a recess in the nuts, as shown in Fig. 4. This recess is preferably in a flange on the nut, and the flange is held between ball bearings on the side plate of the carriage. Normally, any rotation of the shaft 27 will move the arms toward or from each other, but upon pulling out the pin 35 of one arm against the action of the spring 39, and rotating the shaft, that arm will remain stationary because the nut can freely rotate, but the other arm will move in the direction and to the extent desired.

The shaft 27 is driven by a reversible motor 36 which, as shown in Fig. 9, has a pinion 37 connected through a train of speed reducing gears 37' and 37" to a gear 38 keyed on the shaft 27. To grip a roll between the arms, the motor 36 is started in the proper direction to bring the two arms toward each other and engage the chucks, hereinafter described, into the ends of the core of the roll. To prevent stalling of the motor when the chucks are in the desired positions in the roll, there is provided a slip friction clutch in the driving connection between the motor 36 and the shaft. This is shown as a clutch member 40 secured to the gear 37 and a cone 41 keyed on the shaft of the motor and held in by a spring, as shown in Fig. 10.

For moving the arms simultaneously in the same direction properly to align the sheet with the work or the sheet receiving machine, there is provided means for moving the shaft 27 endwise without rotating it, and to thereby carry both arms to the proper position. One means for accomplishing this result is shown particularly in Fig. 11.

One end of the shaft 27 is mounted in bearings in a socket 42 which is slidable in a tubular casing 43. The bearings are of a thrust type, so that any endwise movement of the socket 42 results in a corresponding endwise movement of the shaft 27, but the shaft may freely rotate in the socket. The socket 42 is so held in the casing 43 that rotation of the socket is prevented. This may be effected by any suitable means, such as a key 44. The socket 42 is provided with an extension 45 which is threaded in a nut 46 mounted in thrust bearings for rotation in the casing 43. The outer end of the nut is secured to a gear wheel 47 which meshes with a pinion 48 on the same shaft 49 as is a large gear 50, and this last mentioned gear meshes with a pinion 51 of a reversible motor 52. Thus, by means of this motor the nut 46 may be rotated to move the threaded member 45 endwise in either direction, and thus pull or push the shaft 27 with the roll supporting arms axially to the desired position. The motor may be mounted in any suitable position. In Fig. 11 it is shown next to the motor 36, but in Fig. 9 it is indicated as being below the motor 36 and in front of the threaded extension 45.

As previously noted, the arms 26 are movable along the shaft 27, and are held through sleeve 26a in bearings 28 on the side plates 29 of the carriage. For swinging the arms vertically to raise or lower a roll, there is provided a screw jack including a jack shaft 54 extending transversely of the machine parallel to the shaft 27 and supported in bearings 55 (Fig. 2). On this shaft there are a pair of worms 56 each meshing with a corresponding worm wheel 57 disposed in a horizontal plane below the rear end of its corresponding arm 26 and held against rotation in respect to the jack shaft by a key 54a. Thus, as the arms 26 are adjusted toward and from each other along the shaft 54 by rotation of the shaft 27, the bearings 55 will move the worms 56 along the shaft and keep them in mesh with their respective worm wheels 57. This worm wheel is mounted on a roller bearing 58 and is rigidly connected to a socket member 59 which has a spherical surface engaging a ball member 60 on an upright screw 61. The lower end of this screw shaft is seated on a thrust bearing 62 having a ball head concentric with the surface of the ball member 60. The ball member 60 is provided with a pair of stub shafts 63 provided with bear-

ing blocks 64 slideable in vertical slots in a ring 65 which is secured to or integral with the socket member 59. Thus the shaft 61 may swing on the thrust bearing and slide in the socket 59 without interrupting its drive connection from the shaft 54. The upper end of the screw shaft 61 is threaded in a nut 67 which is journaled on pins 68 mounted in the two side branches or forks 26' of the arm 26 which is disposed between and held against lateral movement by the side members 29 of the carriage.

The shaft 54 at one end is connected by gearing 71a to a reversible motor 71. In Fig. 1 this motor is shown at the opposite end of the machine from the motors 36 and 52, but in Fig. 9 all of the motors are shown at the same end. Thus, by energizing the motor the shaft 54 may be rotated in either direction and the power transmitted through the gearing 56, 57, and the swivel joints 63, 64, to rotate the screw shaft 61. As this shaft rotates, the arms 26 are swung in vertical planes to raise or lower the roll. As the arms are pivoted, the nut 67 travels in an arcuate path, and the screw shaft 61 swings about the thrust bearing 62, but power is properly transmitted to the screw shaft regardless of the angular tilt of the latter.

In some cases it is desirable to raise or lower one arm in respect to the other so as to draw paper more effectively if the roll be tighter at one end than at the other. To permit this, one of the arms has its gear 56 keyed on or integral with a sleeve 69 normally locked against rotation in respect to the shaft. As shown in Fig. 2, there is provided a sleeve 70 keyed to the shaft and having lugs 72a normally engaging sockets 72 in the end of the sleeve 69 so that the parts must rotate together. The sleeve 70 is held in locked position by a spring 73, and may be pulled out against the spring by a handle 74. Normally the parts are in the position shown in Fig. 2, but by pulling the sleeve 70 out against the spring, the sleeve 69 is released from the shaft so that by rotating the shaft 54 the other arm may be raised or lowered without changing the position of the released arm, because it is held by the self-locking gearing 56, 57. Various other means may be employed to adjust one arm vertically without adjusting the other, and normally all of the motors and gears are enclosed in a protecting casing, as shown at 75 in Figs. 12 and 13.

The roll may be supported by and between the two arms 26 in any suitable manner. As shown particularly in Figs. 3, 5 and 6, each arm at its outer end has a transverse pin 83 journaled in suitable bearings, and the pin at one end has a conical chuck 84 which may be forced into the end of the roll by the movement of the arms toward each other through the rotation of the shaft 27. Each pin 83 at the outer end has a brake drum 85, and pivotally mounted on the side of the arm are a pair of brake shoes 86 which may be applied with the desired pressure against the brake drum by means of a clamping screw 87. Thus the tension on the sheet while it is being unwound may be varied as desired.

A modified form of expanding chuck is shown in Fig. 6. Here the chuck 84' has a number of longitudinal grooves 90 arranged around a conical surface, and with the inner sides of each groove inclined to the axis. A shoe 91 slides in this groove and is pushed endwise by a spring 92 engaging the collar 93. The chuck is inserted in the end of the roll, and as it is forced into the roll the collar 93 forces the shoe along the

inclined grooves, the shoe is forced outwardly, and as it slides back the roll is tightly clamped on the chuck. The spring re-positions the collar and shoe when the chucks are drawn out of the roll.

As one important advantage of applicant's novel construction, and as one important feature of it, the apparatus which is shown at the left of the main vertical frame plate 22 may be duplicated upon the opposite side, and each lifting mechanism provided with its own actuating motors and driving connections. While a roll of material supported on one pair of arms is being delivered, a second roll may be brought into place and mounted between the arms on the other side of the frame, and adjusted to the proper position. Thus, as soon as one roll is exhausted, the sheet from the other roll may be immediately delivered without stopping the machine. In some cases it is desired to employ a sheet of greater width than that of any rolls in stock, as shown in Fig. 12. In that case, the arms on one side of the frame are so adjusted in respect to the position of the arms on the other side that two sheets, A and B, may be delivered at the same time, in slightly overlapping position. Such a sheet may be the liner sheet or the inner corrugated sheet in the manufacture of corrugated board, or may be for any other purpose for which the sheet receiving machine is designed or intended.

The arms are of such length that when in raised positions rolls may be moved axially beneath the arms to proper positions directly beneath the ends of the arms, so that they may be readily engaged by the chuck when the arms are lowered, and whereby when the rolls are lifted by the arms, this web on one side of the cross frame may pass freely over the latter and be delivered in the desired overlapping relationship to the web delivered from the other roll.

Having thus described my invention, what I claim as new and desire to secure by Letters Patent is:

1. A mill roll stand having a stationary cross frame, a pair of carriages supported thereby, a pair of arms, one pivoted on each carriage for supporting a roll therebetween, a shaft with right and left hand threaded parts for moving said carriage toward and from each other, said arms being pivoted about the center of said shaft and having nuts engaging said threaded portions and held against endwise movement in respect to said arms, and means for rotating said shaft.

2. A mill roll stand having a stationary cross frame, a pair of carriages supported thereby, a pair of pivoted arms, one mounted on each carriage for supporting a roll therebetween, a shaft, means operatively connecting said shaft to said arms, means for rotating said shaft to move said arms toward and from each other along said frame, means for moving said shaft endwise to move said arms along with and in the same direction as the shaft, and means for swinging said arms about said shaft as a center.

3. A mill roll stand having a stationary cross frame, a pair of carriages supported thereby, a pair of shafts supported by said frame, a pair of arms, one mounted on each carriage, and both pivoted about the center of one of said shafts, and means connecting said arms to the other shaft for swinging said arms about their pivotal center.

4. A mill roll stand including a stationary cross frame, a pair of carriages slideable therealong, a

pair of parallel arms, one pivoted on each of said carriages for supporting a roll, a pair of upright screw jacks on said carriages each engaging a corresponding one of said arms for swinging them in vertical planes, and means for operating said screw jacks simultaneously.

5. A mill roll stand including a pair of carriages movable toward and from each other, arms pivoted intermediate of their ends on said carriages, a pair of parallel shafts, means at one end of each of said arms for supporting a roll, means at the opposite end of each of said arms and operatively connected to one of said shafts for swinging said arms in vertical planes, and means operatively connected to the other shaft for moving said arms toward and from each other. 10

6. A mill roll stand including a frame, a pair of carriages thereon and movable toward and from each other, a pair of arms pivoted intermediate of their ends on said carriages, means at one end of each of said arms for supporting a roll, a pair of substantially vertically disposed screw shafts one at the other end of each of said arms, and means for rotating said screw shafts and thereby swinging said arms in vertical planes. 15

7. A mill roll stand having a frame, a pair of carriages supported thereby and movable therewith, a pair of horizontal shafts, a pair of arms pivotally mounted to swing about the center of one of said shafts, means for moving said last mentioned shaft endwise to impart corresponding movement to said arms, means for rotating said last mentioned shaft and thereby moving said arms toward and from each other, and means for rotating the other shaft and thereby swinging the arms about the first mentioned shaft as an axis. 20

8. A mill roll stand including a frame, a pair of carriages mounted thereon and movable toward and from each other, a pair of arms, one pivoted on each carriage, an upwardly extending jack shaft pivotally mounted on each carriage and having threaded engagement with its corresponding arm, and means engaging each jack shaft adjacent to its pivotal center for simultaneously rotating said jack shafts to swing said arms. 25

9. A mill roll stand including a pair of carriages, a pair of shafts each journaled in both carriages, a pair of arms, one pivotally supported on each carriage, means for swinging said arms upon rotation of one of said shafts, means for moving said carriages toward and from each other upon rotating the other shaft, and means for moving said arms simultaneously in the same direction and lengthwise of the stand upon endwise movement of said last mentioned shaft. 30

10. A mill roll stand including a cross frame, two parallel shafts journaled therein, a pair of

carriages movable along said frame, a pair of arms, one pivotally mounted on each carriage, means on said carriages for swinging said arms upon rotating one of said shafts, means for moving said arms toward and from each other upon rotating the other shaft, and means on said frame for moving said last mentioned shaft endwise to move said carriages and arms simultaneously in the same direction. 5

11. A mill roll stand including a frame, a shaft journaled therein, a pair of carriages movable along said frame, a pair of arms, one pivotally mounted on each carriage, means for moving said arms and carriages toward and from each other upon rotating said shaft, and means for moving said shaft endwise to simultaneously move said arms and carriages in the same direction. 10

12. A mill roll stand having a stationary frame, a pair of carriages movable along said frame, a pair of arms one pivotally mounted on each carriage, a pair of upright screws one on each carriage and operatively connected to the corresponding arm, a transverse shaft, and gearing on each carriage operatively connecting said transverse shaft to its corresponding screw and slidably along said first mentioned shaft as said carriages are moved along said frame. 15

13. A construction as defined in claim 12, in which the screws are pivotally connected to said gearing. 20

14. A mill roll stand having a frame, a pair of carriages movable along said frame, a pair of roll lifting arms each pivotally mounted on a separate one of said carriages, a shaft on said frame and having right and left hand threaded connections to said carriages respectively, whereby upon rotating said shaft said carriages are moved toward and from each other, and means for moving said shaft endwise to bodily move said carriages in the same direction. 25
